J. BRICKETT.
End Gate for Wagons.

No. 229,029.

Patented June 22, 1880.

UNITED STATES PATENT OFFICE.

JOHN BRICKETT, OF DANFORTH, ILLINOIS.

END-GATE FOR WAGONS.

SPECIFICATION forming part of Letters Patent No. 229,029, dated June 22, 1880.

Application filed October 13, 1879.

To all whom it may concern:

Be it known that I, JOHN BRICKETT, of Danforth, in the county of Iroquois and State of Illinois, have invented certain new and useful Improvements in End-Gates for Wagon-Beds, of which the following is a specification.

This invention relates to that class of end-gates which are made detachable for convenience in unloading the contents of the bed.

10 The object of this invention is to produce an end-gate which can be readily and quickly detached, and which, when attached, will be firmly secured in position.

To this end my invention consists of a slotted 15 plate provided with a transverse diaphragm to receive one end of the gate, upon the opposite end of which is pivoted an L-shaped strap, slotted near its free end to receive a staple, and provided with a spring-actuated catch to 20 secure the strap, and with it the end-gate, to the opposite side of the bed.

My invention also consists in certain details of construction, which will hereinafter be fully described and claimed.

25 In the accompanying drawings, in which similar letters of reference indicate like parts, Figure 1 is a perspective of one end of a wagon-bed provided with my end-gate. Fig. 2 is a similar view of the pivoted strap and its spring- 30 actuated catch on an enlarged scale. Fig. 3 is a perspective of the slotted bracket, showing its transverse diaphragm; Fig. 4, a section of the end-gate, having its end slotted to fit over the diaphragm in the groove of the 35 bracket-plate.

A represents a wagon-bed of the usual construction, having secured to one of its side-boards, by screws or bolts, a bracket-plate, B, provided with a vertical groove to receive one 40 end of the gate B'. Toward the upper end of this bracket-plate is a diaphragm, b, extending across it, the gate being provided with a corresponding slot to receive the same, whereby, when in position to close the end of the 45 bed, the gate will be prevented from working up or down in the groove of the plate.

To the opposite side-board and upon its inner side, at a distance from its end corresponding with the thickness of the end-gate, is se- 50 cured an upright or bracket, C, forming an abutment for the end-gate, to prevent its be-

ing forced inwardly. Upon the outside of and near this end of the gate is secured a plate, D, to which is pivoted the L-shaped strap E, so that it can be, when securing the gate in position, swung around so as to embrace the end and side of the bed. The free end of this strap is provided with a longitudinal slot correspond- 55 ing with a staple, F, secured to a plate, F', upon the outside of the side-board.

To the strap, at a suitable distance from its slot, is pivoted a catch, G, which, when the strap is in position upon the staple, will drop through the latter and lock the strap on the same.

H is a headed bolt or pin, forming the pivot 60 for the catch G, and extending outwardly beyond said catch, so as to form a bearing for a coil-spring, h, wound about it, and having one of its ends secured by passing it through a perforation in the strap, as shown at h', and clinched upon the opposite side. The other or free end of the spring h is extended at right angles to the pivot H, so as to bear upon a 65 stud or projection, i, upon the catch.

By this construction it will be seen that the catch G is thus made spring-actuated, so that it will, when in any position, have a tendency to press downwardly, and when held in the staple it will be prevented from slipping out 80 of the same by jarring, &c., when the wagon is in motion, thereby securing the catch against accidental detachment.

In detaching my end-gate the operation is as follows: I first take hold with one hand of the stud on the catch, raise it out of the staple, and with the other hand swing the strap around until it is released from the side-board, and with the same movement the end of the gate to which the strap is attached is swung outwardly, thereby detaching its opposite end from the grooved bracket.

In order that the end of the gate resting in the groove of the bracket may be readily detached, it is rounded upon its inner corner, 95 so that it will not impinge against the inner wall of the groove.

Having thus described my invention, what I claim, and desire to secure by Letters Patent, is—

1. The combination, with the end-gate of a wagon-bed, of a longitudinally-slotted plate,

B, provided with a diaphragm, *b*, to receive one end of said gate, a strap, E, upon its other end, provided with a spring-actuated catch, whereby the gate is prevented from vertical movement and held rigidly in position to close the end of the wagon.

2. The combination, with the hinged strap E, staple F, and hook or catch G, of a depressing-spring upon the pivot of said hook to hold it in position, so as to prevent its accidental detachment when locking the strap.

3. A wagon-bed provided with a longitudi-

nally-grooved plate, B, provided with a diaphragm, *b*, plate F', staple F, in combination with an end-board having attached thereto a pivoted and slotted strap, D E, provided with a catch, G, pivot H, spring *h*, and stud *i*, substantially as and for the purposes described and set forth.

JOHN BRICKETT.
